UNITED STATES PATENT OFFICE.

ALVA LEMAN REYNOLDS, OF LONG BEACH, CALIFORNIA.

FIRE-EXTINGUISHING SYSTEM AND APPARATUS.

1,193,064.

Specification of Letters Patent. Patented Aug. 1, 1916.

Application filed October 22, 1912. Serial No. 727,243.

To all whom it may concern:

Be it known that I, ALVA LEMAN REYNOLDS, a citizen of the United States, residing at Long Beach, in the county of Los Angeles and State of California, have invented a new and useful Fire-Extinguishing System and Apparatus, of which the following is a specification.

An object of this invention is to provide improved security against damage and loss from fire in buildings, towns and cities, and the invention includes the system and the specific apparatus and parts and combinations of parts hereinafter more particularly set forth.

An object of this invention is to make provision whereby efficient fire extinguishing apparatus can be constantly kept in readiness at minimum expense to be put into immediate use for extinguishing the fire without waiting on engines or pumps, and whereby the cost of maintaining this system and keeping it in readiness for use will be minimized.

The principle of this invention is that a supply of water is constantly maintained under a fire pressure, as, for instance, from 100 to 120 pounds per square inch, and there is established and maintained a body of compressed air under a high pressure, say 500 pounds, more or less, per square inch, and sufficient to expel from the water container, at the fire pressure, all of the water contained therein, said container being connected with fire apparatus such as fire plugs and hose at the places where conflagration might occur. Provision is also made whereby water may be supplied to the reservoir during the operation of discharging water from the container at the fire pressure, it being possible by the air storage to utilize a maximum amount of water under the fire pressure with a given amount of power at the pumping plant.

The invention is applicable for the protection of isolated buildings, bridges, wharfs and other structures, singly in connection with one unit, or any desired number of buildings in connection with a single pumping plant or with a plurality of pumping plants.

The invention is especially designed for use at beach resorts or other places where ocean water or a constant supply from river or lake is available, and it is also applicable where water is obtained from wells having

limited capacity so that a large number of wells from widely scattered territory may be brought into requisition for extinguishing fire in a limited locality when desired.

A further object of the invention is to provide a fire extinguishing system in which a large number of units may be employed in the most satisfactory and economical manner for the extinguishing of fires in the vicinity of each unit, thus giving economical protection for various sections of a city and also to make provision whereby the action of all of the units may be concentrated upon any one locality.

This invention is more particularly intended for use in localities where gravity pressure is not available and where it is now customary to employ fire engines to produce the fire pressure necessary to make the water effective in putting out the fire, but it is understood that the system may be in the nature of an emergency system to be operated either independently or in conjunction with the present fire extinguishing systems where artificial power is supplied to produce the fire pressure.

A further object of the invention is to enable a growing town to have a complete fire protection plant supplied at minimum cost and capable of being increased by cumulative extensions as the town grows.

The accompanying drawings illustrate the invention.

Figure 1 is a fragmental plan of a system constructed and installed in accordance with this invention and showing one supply unit of the system intact. Fig. 2 is an elevation of the unit shown in Fig. 1 and a fragment of the system in which it is connected. Fig. 3 is a detail side elevation of the automatic air regulating device showing one of the combined pneumatic and spring motors partly in section; the air valve being closed by the standing pressure of the water container side. Fig. 4 is a diagrammatic plan of a system embodying the invention. Fig. 5 is a detail of one of the automatic reverse-flow by-pass connections between two supply units.

Referring first to Fig. 4, the system there shown comprises three water main districts or sections A, B, C, each comprising water mains D having intersections E and fire plugs F, said mains of the different districts being connected together by automatic reverse flow connections G detailed in Fig. 5, each of

which connections consists of a by-pass having two limbs H, I, and two by-pass valves J, K, there being a pipe L connected with a main on one side of the by-pass connection, and with a combined spring and pressure valve motor M that is arranged to be acted on by the pressure in the main to close the valve when the pressure from the supply side reaches the maximum fire pressure, 5 said motor being provided with springs N to open the valve when the pressure is lowered from any reason as the discharge of water from the fire extinguishing devices which may be hose nozzles or other suitable 10 apparatus.

The supply units P, Q and R are connected with the water main sections A, B, C, respectively, and are separated by the automatic connections G. It is understood 20 that said supply units are located at places where water is available from wells S or any other suitable source, and are distributed throughout the system in a practically uniform manner.

25 Referring more particularly now to Figs. 1, 2 and 3 which illustrate a supply unit, it is to be understood that the same includes a water pumping and storing apparatus T and an air compressing and storing apparatus U arranged to work automatically to supply water under a determined pressure to the main.

The water container 1 may be formed of a plurality of tanks 2 constructed of boiler- 35 iron or steel and are of as small cross-sectional area as deemed practical, thus to afford at small cost, a desired capacity with sufficient strength to withstand a pressure considerably above that required for fire extinguishing purposes.

The tanks of each container are connected by means of inlet pipes 3 and outlet pipes 4, and means are provided for supplying air pressure to said tanks so that the water 45 stored in the tanks may be constantly available through the outlet pipes 4 which open from the bottom of the tanks into the main 5, that is connected with the system of water mains D which lead to the various places 6 at which fires are liable to occur, and are connected there with fire extinguishing apparatus as the nozzles 7.

The water tanks 2 are of such radius as to be practical for containing the water under the determined working or fire pressure with a required co-efficient of safety. The water tanks are supplied with water from a pump 8 through a pipe 9 controlled by check valve 10 and connected with the inlet 60 pipes 3. Said container should have a desired capacity calculated to be amply sufficient for any emergency that may be required of it, and the capacity of the container may be increased by increasing the 65 number of the tanks. The air receiver 11

is also composed of a plurality of tanks, and each of the air tanks 12 is of such strength as to sustain a comparatively high pressure, say 500 pounds per square inch; and with this object in view said tanks are of smaller 70 diameter than the water tanks, say, for instance three feet in diameter and fifteen feet in height, more or less, so as to have a coefficient of safety under the higher pressure without excessive cost of material. 75

The air compressor 13 is connected with the air tanks 12 by a pipe 14 having a check valve 15, the connection being made directly with one of said tanks; and the tanks are connected together at the top by the air 80 pipes 16 from which the air supply pipe 17 leads to the tops of water tanks 2 that are connected at the top by the water container air connections 18 which open into the tops of the tanks. The air pipe 17 is provided 85 with a regulating valve 19 that is controlled by a combined pneumatic and spring motor a consisting of the cylinder 20, piston 21 inside said cylinder, piston rod 22 connected therewith and yielding means 23 to return 90 the piston against the air pressure; the cylinder being connected by the motor pipe 24, with the air pipe limb 17' between the valve 19 and the water container; and the piston rod 22 being connected with the valve arm 95 25, the force of the yielding means 23 is exerted to normally open the valve when the pressure in the water container is lowered nearly to the desired fire pressure, say below a static pressure of about 125 pounds, 100 and is capable of being overcome by the action of the air against the piston 21 whenever the pressure in the limb 17' somewhat exceeds the required fire pressure. The tension of the springs may be regulated by tension bolt and nut 26, 27, to make the apparatus more or less sensitive. The water container air pipe limb 17' is connected by the water motor controller air pipe 28 with a pump controlling motor b that is of the 110 same construction as the motor a, the piston rod 29, however, being connected with the electric switch 30 and adapted to normally close said switch when the pressure in the limb 17' falls below the static pressure of 115 the water container and the limb 17' determined by the motor a; the electric switch 30 for the pump motor 31 being normally held open by the air pressure in the motor b and closed by the force of the springs 23' 120 when the pressure falls below the static pressure to which the apparatus is set, so that whenever water is allowed to flow from the water container, the springs 23' close the switch 30, thus supplying energy from 125 the electric system 32 to drive the water pump 8. The air compressor 13 is operated by an electric motor 33 which receives energy from the electric system 32 through a switch 34 that is controlled by the high 130

pressure motor *c* which is of the same construction as the motors *a* and *b* but of less size, being operated by the high pressure of the compressed air receiver 11 with which said motor *c* is connected by the high pressure air pipe 35. The spring means 23" of said motor are adjusted to close the switch 34 when the pressure in the air receiver 11 falls below the normal static compressed 10 pressure, say 500 pounds per square inch.

In practical operation, the pressure gages 36, 37 are connected with the high pressure and working or fire pressure sides respectively of the apparatus, and the pipe 28 is 15 provided with a relief pet cock 38.

The pump 8 is connected by its intake pipe 39 with any suitable source of supply as the well S.

In practice when the water containers 20 and the air receiver are empty, the spring side of the motors *a*, *b* and *c* will be active, opening the valve 19 and closing the switches 30 and 34; and the pump motor 31 and air compressor motor 33 will operate the pump and air compressor to fill the tanks. When the pressure in the water container 1 has risen to the normal static pressure, the pneumatic sides of the motors *a* and *b* will operate to close the valve 19 and 30 to open the power switch 39, thus stopping the pump 8 and preventing the pressure from rising any higher in the container. The spring side of the high pressure motor *c*, however, remains active until the pressure in the air receiver rises to the normal static high pressure, say 500 pounds, and thereupon said switch is closed and the whole apparatus becomes quiescent. Whenever a water plug of the system is opened, 40 the pressure in the water container is immediately lowered and the spring sides of the motors *a* and *b* operate respectively to open the valve 19 and close the switch 30, thus immediately bringing up the pressure.

45 In Fig. 4 it is assumed that owing to highly inflammable conditions a sudden and great conflagration is raging in block 6' at the upper left corner of the view and it will be noted that all of the fire plugs immediately available for use on said block are indicated as being connected with fire hose 7, thus creating a large demand for water at that part of the system. The heavy black arrows in the body of the view indicate the flow of water from the several supply units toward said block 6' to supply such demand. In the lower left corner another fire apparatus is shown in action in block 6'', and lighter arrows indicate the 50 flow of water toward that point from the unit R. It will be understood that the heaviest flow of water will be toward the heaviest demand on the mains and that a sufficient flow to every point of demand will 55 continue until the air pressure is exhausted.

It is assumed that the storage capacity for any section will be sufficient to take care of any fire that is liable to occur provided the fire apparatus is put to work at the incipiency of the fire and that only on extraordinary occasions will the whole system be called into operation as suggested in Fig. 4.

After the emergency is over, the water container may again be filled with water and the system thus made ready for future 75 action. In the process of making ready it may be found necessary to open the pet-cock 38 to allow air to escape from the water container sufficiently to allow said container to be properly filled with water.

The water in the several containers together with the air pressure in the air receivers represent the storage supply of water always held in excess of the capacity of the pumps, and this surplus storage serves as 85 a reinforcement of the supply always on hand in case of emergencies which can be brought into play in excess of the amount of water obtainable from the different pumping plants in the system.

90 By means of the reverse flow by-pass connections, the static pressure and the supply unit of each district remain undisturbed during normal fire action in any other district; and when the drain on such other 95 district is excessive, the pressure in the remaining districts is at once available therefore through the by-pass connections.

The springs of the motors J, K, for the by-pass valves of each district are set so 100 that the water pressure from the main D of a district acting through the pipe L of the cylinder M of such motor will allow the spring N to open the valve when the pressure in the main D falls a few pounds below the static fire pressure of the units, thus allowing the static fire pressure of each system to be maintained at the normal in each district independently of the others until the demand at plugs within that district or 110 an emergency demand from other districts is sufficient to exhaust the high pressure in the receiver.

The storage of air may not only be sufficient to expel the water from the container, 115 but may also be sufficient to expel water from some part of the mains through the plugs F or other outlet and it is deemed desirable to allow the air to escape at the pet cock 38 whenever the system is being 120 again filled with water.

I claim:

1. A fire extinguishing system comprising a water container; means to supply water thereto under pressure; means to discharge 125 water from the container under a predetermined pressure; an air receiver; means to supply air to the air receiver under pressure exceeding said predetermined pressure; means to conduct air from the air receiver 130

to the water container; mechanism to cut off and control the flow of air through said conducting means; means connected with and operated by the pressure in the water container to automatically open the cut-off mechanism when the pressure in the water container falls below the predetermined pressure and to close the cut-off when the pressure in the water container exceeds said predetermined pressure; means operated by the pressure in the water container to start the water supplying means into operation when the water pressure in the container falls below the predetermined pressure, and means operated by the pressure in the air container to start the air compressing means when the pressure in the air container falls below its maximum and continue to operate until the required air pressure is reached even after the air-supplying means has been cut off.

2. In an automatic fire extinguishing apparatus comprising a water-containing tank supplied with air pressure; an air-containing tank supplied with air under a pressure exceeding the air pressure in said water-containing tank, regulating means between the water-containing tank and the air-containing tank whereby air pressure from the latter may be conveyed to the former, the combination of an electrically-operated air compressor for maintaining the required pressure in said air-containing tank, switch connections for controlling said electrically-operated compressor, and automatic means for making and breaking said switch connections for starting and stopping the air compressor according to the needs and demands of pressure conditions in said tanks.

3. In a system of the character described having a water-containing tank, an air-containing tank, a pump to supply water to said water-containing tank and to refill it whenever water is being withdrawn therefrom, an air compressor for compressing the air in said air-containing tank, regulating means between said water-containing tank and air-containing tank for supplying air pressure to said water-containing tank from said air-containing tank and thereby maintain the required pressure in said water-containing tank, the pressure in said air-containing tank exceeding the pressure being conveyed to the water-containing tank, means for simultaneously operating said pump and air compressor to replenish water to said water-containing tank and air to said air-containing tank, respectively, and

means to operate said air compressor even after said pump has come to rest to continue to supply air under pressure to said air-containing tank until the required pressure is obtained in said air-containing tank.

4. An automatic fire extinguishing apparatus comprising one or more water containing tanks supplied with air pressure; one or more air-containing tanks supplied with air under pressure; and regulating means between the water-containing tanks and the air-containing tanks whereby pressure may be conveyed from the latter to the former; automatic means for replenishing said air-containing tanks whenever air is drawn from it to said water-containing tank; said means comprising electrically-operated air compressors, switches, means sensitive to the pressure of said air-containing tanks adapted to throw said switches into contact to operate the air compressors whenever the air pressure in said air-containing tanks falls and to throw said switches out of contact when the air pressure has been restored.

5. In an automatic fire extinguishing apparatus comprising a water-containing tank supplied with air pressure, an air-containing tank supplied with air under a pressure exceeding the air pressure in said water-containing tank, regulating means between the water-containing tank and the air-containing tank whereby air pressure from the latter may be conveyed to the former and to maintain the required pressure in the latter whenever water is being withdrawn from said latter, the combination of an electrically-operated pump for re-filling the water-containing tank whenever water is being drawn therefrom, an electrically-operated compressor for supplying air to the air-containing tank to restore the pressure therein whenever it is being reduced to restore pressure in said water-containing tank, switch connections for controlling said electrically-operated pump and compressor, and automatic means for making and breaking said switch connections for starting and stopping the compressor and pump according to the needs and demands of pressure conditions in said tanks.

In testimony whereof, I have hereunto set my hand at Los Angeles, California, this 17th day of October, 1912.

ALVA LEMAN REYNOLDS.
